US00D830124S

(12) **United States Design Patent** (10) **Patent No.:** **US D830,124 S**
(45) **Date of Patent:** **** Oct. 9, 2018**

(54) **CONTAINER**

(71) Applicant: **VITA-MIX MANAGEMENT CORPORATION**, Olmsted Township, OH (US)

(72) Inventors: **Brenton Krivos**, Brunswick, OH (US); **Jack Warren Gee, II**, Willoughby, OH (US); **Eugene J. Kozlowski**, Medina, OH (US)

(73) Assignee: **VITA-MIX MANAGEMENT CORPORATION**, Olmsted Township, OH (US)

(**) Term: **15 Years**

(21) Appl. No.: **29/557,026**

(22) Filed: **Mar. 4, 2016**

(51) LOC (11) Cl. **31-00**

(52) U.S. Cl.

USPC **D7/413; D7/376; D7/378; D7/386; D7/412**

(58) **Field of Classification Search**

USPC D7/372, 376-386, 412-413, 587, 602, D7/629, 665-666, 669, 679, 693-694; D9/428-429

CPC A21C 1/02; A21C 1/04; A23N 1/00; A23N 1/02; A47J 43/04; A47J 43/25; A47J 43/27; A47J 43/042; A47J 43/044; A47J 43/046; A47J 43/075; A47J 43/0722; A47J 43/0727; A61C 9/0026; B01F 3/00; B01F 3/0807; B01F 3/0853; B01F 13/0059; B01F 13/0064; B02C 1/08; B02C 2/04; B02C 4/42; B02C 4/142; B02C 4/143; B02C 4/423; B02C 13/1835; B28C 5/10; B28C 5/12; B28C 5/14; B28C 5/16; B65D 1/265

FIG. 1 is a perspective view of a container showing our new design;

FIG. 2 is a front side view thereof;

FIG. 3 is a back side view thereof;

FIG. 4 is a first side view thereof;

FIG. 5 is a second side view thereof;

FIG. 6 is a top view thereof; and,

FIG. 7 is a bottom view thereof.

The broken lines shown in the drawings are for illustrative purposes only and form no part of the claimed design.

1 Claim, 3 Drawing Sheets

Primary Examiner — Ricky Pham

(74) Attorney, Agent, or Firm — McDonald Hopkins LLC

(57) CLAIM

The ornamental design for a container, as shown and described.

DESCRIPTION

FIG. 1
